UNITED STATES PATENT OFFICE

110,852

DESIGN FOR A SWEATER ENSEMBLE

Morris Simon, Brooklyn, N. Y.

Application June 9, 1938, Serial No. 77,686

Term of patent 3½ years

To all whom it may concern:

Be it known that I, Morris Simon, a citizen of the United States of America, residing in New York city, in the Borough of Brooklyn, county of Kings, and State of New York, have invented a new, original, and ornamental Design for a Sweater Ensemble, of which the following is a specification, reference being had to the accompanying drawing, forming part thereof, wherein,

The rear portion of the sweater member is plain.

The characteristic feature of my design resides in the specific jacket member in combination with the specific sweater member, as shown.

I claim:

The ornamental design for a sweater ensemble, substantially as shown and described.

MORRIS SIMON.
